VALVE FOR CORE DRILLS

John H. Howard, Whittier, Calif.

Application January 26, 1937, Serial No. 122,385

9 Claims. (Cl. 255—72)

This invention relates to well drilling tools and relates more particularly to a valve for a core drill for use in the rotary method of well drilling. A general object of this invention is to provide a simple, practical valve for the upper end of the core-receiving barrel of a core drill that prevents the entrance of thick mud into the barrel when the tool is run into the well, and that prevents the circulation fluid from entering the barrel during the drilling operation.

It is usually necessary to provide a valve at the upper end of the core receiving barrel of a core drill to prevent the downwardly flowing circulation fluid from washing away the core and that will allow the fluid to escape from the barrel as it is displaced by the core. The typical form of core drill valve now in general use is a simple ball check valve having a ball that seats downwardly to prevent the entrance of the circulation fluid to the barrel and that is adapted to open when the pressure in the barrel exceeds that of the circulation fluid. When a core drill equipped with a typical ball type check valve is run into a well, the valve opens due to the velocity of fluid flow into the drilling string and thus allows the well fluid to enter the barrel. If the mud at the bottom of the bore is very thick it enters the barrel and often clogs the barrel so that it is impossible to obtain a core. Valves have been introduced embodying a ball that is dropped into the drill after the mud, etc. has been flushed from the barrel by water pumped downwardly through the drilling string. This drop-ball type of valve is satisfactory in many instances but cannot be employed where float valves are connected in the drilling string, as such float valves prevent the ball from passing downwardly through the string to the drill.

Another object of this invention is to provide a valve for a core drill that closes when the drill is run into the well and, therefore, prevents mud, etc. from entering the core barrel.

Another object of this invention is to provide a valve for a core drill that may allow the light or clean fluid in the upper portion of the well to enter the barrel, but which remains closed as the drill approaches the bottom of the well, thereby preventing heavy mud in the bottom of the well from entering and clogging the barrel.

Another object of this invention is to provide a core drill valve of the character mentioned that remains closed during the making up of the joints in the drilling string as the string is being run into the well.

Another object of this invention is to provide a

core drill valve that automatically closes when the fluid is circulated through the drilling string preparatory to the drilling operation and that remains closed during the drilling operation to prevent the circulation fluid from washing away the core, but may open to allow the escape of fluid displaced from the barrel by the entering core.

Another object of this invention is to provide a core drill valve of the character mentioned that is entirely automatic in operation and that does not necessitate the dropping of an object through the drilling string and, therefore, is adapted for use in tools operated on a drilling string having float valves.

Another object of this invention is to provide a core drill valve of the character mentioned embodying novel dependable means for holding its parts properly assembled and tightly secured to the inner barrel.

A further object of this invention is to provide a core drill valve of the character mentioned that is simple, and inexpensive to manufacture, install and service.

The various objects and features of my invention will be fully understood from the following detailed description of a typical, preferred form of the invention, throughout which description reference is made to the accompanying drawing, in which:

Fig. 1 is a longitudinal detailed sectional view of a typical rotary core drill showing the improved valve of the present invention on the inner barrel. Fig. 2 is a longitudinal detailed sectional view of the valve, taken substantially as indicated by lines 2—2 on Fig. 3 and Figs. 3 and 4 are transverse detailed sectional views taken as indicated by lines 3—3 and 4—4 on Fig. 2.

The improved valve provided by this invention is adapted to be embodied in or applied to core drills of various types and makes. In the following detailed disclosure I will describe one typical form of the invention as used in connection with a more or less conventional rotary core drill. It is to be understood that the invention is not to be construed as limited or restricted to the specific application of the invention illustrated in the drawing.

The core drill illustrated in the drawing includes an outer barrel 10 to be connected with the lower end of a tubular well drilling string. A sub 11 is provided on the upper end of the outer barrel 10 to facilitate its connection with the drilling string. A sub 12 is connected with the lower end of the outer barrel 10 and carries a

cutter head 13. The cutter head 13 is provided with cutting means for making an annular cut in the earth formation. The particular head illustrated has spaced drag type blades 14 operable to 5 make an annular cut in the formation and leave a core for reception by the drill. An inner barrel 15 is arranged longitudinally in the outer barrel 10 to receive the core. A collar 16 on the lower end of the inner barrel 15 cooperates with a 10 recess in the head 13 to support the inner barrel. The inner barrel 15 extends through the outer barrel 10 with substantial clearance leaving an 15 annular fluid space in the outer barrel. Ports 17 in the collar 16 connect this fluid space with discharge ports 18 in the head 13. A core catcher 19 is provided in the head 13 to grip and retain the core. The blades 14 cut or leave the 20 standing core which is received in the barrel 15 as the drilling progresses. The core catcher 19 is operable to break loose the core and to retain the core in the barrel 15 when the drill is removed from the well.

The improved valve of the present invention includes, generally, a body 20, means 21 for 25 removably securing the body 20 to the upper end of the inner barrel 15, a cage 22 on the body 20, a valve seat 23 in the body 20 connected with the cage 22 and a valve or ball 24 in the cage 22.

The body 20 may be a simple tubular member 30 as illustrated in the drawing. In practice the body 20 may be comparatively short and may have relatively thick walls. The tubular body 20 is adapted to enter the upper end of the inner barrel 15, as will be more fully described. The 35 opposite ends of the body 22 may be flat and normal to its longitudinal axis.

The means 21 for securing the body 20 to the inner barrel 15 is such that the valve may be easily and quickly connected to and removed 40 from the inner barrel. The means 21 includes a coarse steeply pitched thread 25 on the body 20 mating with a similar thread 26 on the barrel 15. In the construction illustrated the inner barrel 15 has a tubular extension connected to its upper end 45 by welding at 27 and this extension carries the thread 26. It is to be understood that the thread 26 may be formed on the barrel 15 and I will consider the above-mentioned extension as a part or continuation of the inner barrel. The thread 25 is preferably an external thread for cooperating 50 with an internal thread 26 on the barrel 15. The threads 25 and 26 are steeply pitched so that the valve body 20 may be quickly threaded in place. The body 20 may have a downwardly 55 facing external shoulder 28 for cooperating with the upper end of the inner barrel 15 to limit downward threading of the body.

The means 21 further includes a latch 29 for preventing unthreading of the body 20. The latch 60 29 is pivotally supported by a pin 30 carried by spaced lugs 31 on the upper end of the body 20. The latch 29 projects downwardly and is partially received in a groove 32 in the exterior of the body 20. The lower portion of the latch 29 is received 65 in a notch 33 in the upper end of the inner barrel 15. It will be apparent how the latch 29 cooperating with the notch 33 prevents turning and unthreading of the body 20. The surrounding and confining outer barrel 10 limits outward pivoting of the latch 29 and may prevent the latch 70 from disengaging from the notch 33.

The cage 22 houses or contains the valve member or ball 24 and in the form of the invention 75 illustrated serves to carry the seat 23 and to guide and stabilize the upper portion of the inner bar-

rel 15. The cage 22 is a tubular member having its lower end in communication with the inner barrel 15 and having its upper end in communication with the interior of the outer barrel 10 and the drilling string. The tubular cage 22 is 5 provided between its ends with a chamber 34 for containing the ball 24. A downwardly facing annular shoulder 35 is provided on the lower end of the cage 22 to seat downwardly against the upper end of the body 20. A reduced portion 36 10 is provided on the lower end of the cage 22 and fits downwardly into the upper portion of the tubular body 20. An annular internal flange 37 is provided in the body 20 and is engaged by the lower end of the said portion 36. The chamber 15 15 34 in the cage 22 has closed side walls and is only open at its upper and lower ends.

It is a feature of the invention that the device or valve includes two spaced opposing seats 23 and 38. The seat 38 is provided at the upper end 20 of the chamber 34 while the seat 23 is provided at the lower end of the chamber, as will be herein-after described. In the simple structure illustrated the seat 38 is a tapered annular face on an internal restriction or flange 39 occurring at the 25 upper end of the chamber 34. The side walls of the chamber 34 preferably converge upwardly to the seat 38 to guide the ball 24 to the seat. The opening in the tubular extension or portion 36 is sufficiently large in diameter to allow the ball 24 30 to cooperate with the seat 23, as illustrated in Figs. 1 and 2.

The cage 22 is preferably provided with a plurality of circumferentially spaced wings or guide ribs 40. The ribs 40 project outwardly or radially 35 from the cage 22 and have outer longitudinal edges adjacent the inner wall of the outer barrel 10 to definitely limit working or tilting of the inner barrel 15. The ribs 40 operate to centralize and stabilize the upper portion of the inner barrel 40 15. The upper ends of the guide ribs 40 may be inclined downwardly and outwardly. In practice the ribs 40 may be integral with the cage 22. One of the ribs 40 is provided at its lower end with an extension or lug 41 adapted to cooperate 45 with a notch 42 in the upper end of the body 20. The lug 41 cooperating with the notch 42 prevents relative rotation between the body 20 and the cage 22. The lug 41 is retained in the notch 42 in the manner to be subsequently described.

The valve seat 23 is provided in the body 20 and the cage 22 and is engageable by the ball 24 when the ball seats downwardly to prevent the entrance of circulation fluid into the core receiving barrel 15. The seat 23 may be a simple annular member or tubular member, as illustrated. In accordance with the invention the seat 23 is threaded upwardly into the lower portion 36 of the cage 22 to have its upper end adjacent the 60 lower wall of the chamber 34. An outwardly projecting annular flange 43 is provided on the seat 23 to engage upwardly against the body flange 37. The flange 43 is preferably provided on the lower end of the seat 23. It will be observed that the flange 43 engaging upwardly against the flange 37 holds the cage downwardly against the body 20 and, therefore, holds the lug 41 in the notch 42. The upper end of the valve seat 23 is provided with a suitably formed 65 sealing face 44 engageable by the ball 24.

The lower end of the seat 23 is provided with two diametrically opposite notches 45. The notches 45 are adapted to receive a tool for threading the seat 23 into the cage portion 36 75

when the valve is assembled. When the seat 23 has been properly threaded in place a bar 46 is arranged through the notches 45 to have its opposite ends at the internal wall of the body 20. The 5 ends of the bar 46 are welded to the body 20 at 47. The bar 46 cooperating with the notches 45 and rigidly secured to the body 20 prevents rotation of the seat 23 relative to the body 20 and the seat flange 43 cooperating with the 10 flange 37 holds the lug 41 in the notch 42 as described above, so that the entire assembly is locked against disconnection and loosening.

The ball 24 may be a plain cylindrical member, as illustrated in the drawing. The ball 24 is proportioned to properly cooperate with the seat 38 and the surface 44 of the seat 23. The ball 24 is movable through the chamber 34 with substantial clearance to permit fluid flow through the chamber when it is unseated from the seats 38 20 and 23. The ball 24 may be a solid metal member. However, it may be hollow or formed of a material of relatively low specific gravity to more readily rise against the seat 38 with fluid flowing upwardly through the chamber 34.

25 In operation the core drill is connected with the lower end of a tubular well drilling string and is run into the well on the lower end of the string. The well bore is usually filled or substantially filled with the rotary mud employed in the rotary 30 method of well drilling. When the drill is run downwardly into the well the drilling string is, of course, empty and the fluid in the well flows upwardly through the inner barrel 15 and through the ports 18 and 17 to pass through the outer barrel 10. The fluid passing upwardly into the inner barrel 15 rushes through the cage 22 at a substantial velocity and raises the ball 24 so that it seats upwardly against the seat 38. The ball 24 engaging upwardly against the seat 38 of course prevents further flow through the cage 22 and thus prevents the further entrance of fluid into the inner barrel 15. It will be apparent that the fluid received in the inner barrel 15 prior to closing of the valve 24 is the fluid in the upper 35 portion of the well bore. The fluid standing in the upper portion of the well bore is light and carries a minimum of solid matter in suspension as such solid matter tends to settle in the well. Thus the inner barrel 15 is occupied by clean and 40 relatively light fluid or liquid.

The ball 24 remains closed against the seat 38 as the drill is run through the bore to its lower end. In running a drilling string into a well it is necessary to connect or make up threaded 45 connections in the string. During these operations the drilling string does not move downwardly. However, the column of fluid standing in the well around the outer barrel 10 and the drilling string is higher than the column of fluid 50 in the string so that a differential in pressure exists which maintains the ball 24 upwardly against the seat 38. Accordingly, the ball 24 remains in cooperation with the seat 38 during the running of the tool into the well. When the core 55 drill approaches the lower end of the well bore occupied by the heavy thick mud this mud is prevented from entering the inner barrel 15 by the relatively light and clean fluid completely occupying the inner barrel.

70 When the drill is in position at the bottom of the well the circulation fluid is pumped downwardly through the drilling string to discharge from the core drill. This downwardly flowing circulation fluid flows through the outer barrel 10 75 to discharge from the ports 17 and 18 and, of

course, tends to flow downwardly through the cage 22 and the inner barrel 15. The fluid thus pumped downwardly through the drill moves the ball 24 downwardly against the seat surface 44. The ball 24 engaging the seat surface 44 prevents the downward flow of circulation fluid into the inner barrel 15. Thus the ball 24 prevents the circulation fluid from entering the inner barrel to wash away the core as the core is received in the inner barrel 15. When the upstanding core 10 enters the inner barrel 15 it tends to displace the fluid upwardly from the inner barrel. When the pressure on the fluid in the inner barrel becomes greater than the pressure on the circulation fluid the ball 24 raises from the seat surface 44 and 15 permits the escape of the trapped fluid from the inner barrel 15. As described above, the fluid trapped in the inner barrel 15 is a light, relatively clean fluid and does not interfere with the free entrance of the core to the barrel 15.

20 The core drill valve provided by the invention operates to prevent the entrance of thick, heavy mud into the core receiving barrel when the drill is run into the well. This is important as it prevents such heavy mud from clogging the inner barrel to interfere with the reception of the core. The valve is also effective in preventing the downwardly flowing circulation fluid from entering the inner barrel to wash away the core. The body 20 of the valve may be easily and quickly 25 threaded onto the inner barrel 15 and is dependably locked in place by the latch 29. The removable cage 22 and the releasable seat 23 are securely latched or locked to the body 20 by the lug 41 and the bar 46 and cannot become displaced. The seat 23 and the cage 22 may be readily replaced when worn. The valve is easy to install and is dependable in operation.

30 Having described only a typical preferred form and application of my invention, I do not wish to 40 be limited or restricted to the specific details herein set forth, but wish to reserve to myself any variations or modifications that may appear to those skilled in the art or fall within the scope 45 of the following claims:

Having described my invention, I claim:

1. In a well core drill having a core receiving barrel, the combination of, a cage structure on the upper end of the barrel having a chamber, valve seats at the upper and lower ends of the chamber, the wall of the chamber being inclined upwardly and inwardly toward the seat at the upper end of the chamber, and a movable valve member in the chamber for cooperating with the 50 seats.

2. In a well core drill having a core receiving barrel, the combination of, a body, steep threads connecting the body with the barrel, latch means preventing unthreading of the body, a cage on the body, and means controlling fluid flow 60 through the cage.

3. A valve for use on the core receiving barrel of a well core drill including, a body connected with the upper end of the barrel, the body having a notch, a cage seating on the body, a part on the cage cooperating with the notch, means holding the cage against the body, and a valve member in the cage controlling fluid flow 65 therethrough.

4. A valve for use on the core receiving barrel 70 of a well core drill including, a body connected with the upper end of the barrel, the body having a notch, a cage seating on the body, a part on the cage cooperating with the notch, means holding the cage against the body, a seat threaded in the 75

cage, a non-rotatable connection between the seat and the body, and a valve member in the cage for cooperating with the seat.

5. A valve for use on the core receiving barrel of a well core drill including, a body connected with the upper end of the barrel, the body having a notch, a cage on the body having a multiplicity of external ribs, one of said ribs cooperating with the notch, a seat threaded to the cage, a non-rotatable connection between the seat and the body, and a valve in the cage cooperating with the seat.

6. A valve for use on the core receiving barrel of a well core drill including, a body connected with the upper end of the barrel, the body having a notch, a cage on the body having a lug cooperating with the notch, a seat threaded to the cage and cooperating with the body to hold the cage where the lug is in the notch, means preventing unthreading of the seat, and a ball in the cage for cooperating with the seat.

7. A valve for use on the core receiving barrel of a well core drill including, a body connected with the upper end of the barrel, the body having a notch, a cage on the body having a lug cooperating with the notch, a seat threaded to the cage and cooperating with the body to hold the

cage where the lug is in the notch, the seat having a notch, a bar secured to the body and cooperating with the notch in the seat to prevent unthreading of the seat, and a ball in the cage for cooperating with the seat.

8. A valve for use on the core receiving barrel of a well core drill including, a body connected with the upper end of the barrel, the body having a notch, a cage on the body having a lug cooperating with the notch, a seat threaded to the cage and cooperating with the body to hold the cage where the lug is in the notch, a second seat in the cage spaced above and opposing the first mentioned seat, a ball in the cage for cooperating with the seats, and means preventing unthreading of the first mentioned seat.

9. In a well core drill having a core receiving barrel, the combination of, a tubular valve cage having an upwardly and inwardly inclined side wall, means removably securing the cage to the said barrel, valve seats at the upper and lower ends of the cage, one of said seats being removable, and a ball in the cage operable to cooperate with the seats, said inclined side wall guiding the ball to the upper seat.

JOHN H. HOWARD.
